DESIGN FOR A VESTEE

Florence Lustig, New York, N. Y.

Application March 22, 1944, Serial No. 113,007

Term of patent 7 years

(Cl. D3—16)

To all whom it may concern:

Be it known that I, Florence Lustig, a citizen of the United States and a resident of New York, in the county and State of New York, have invented the new, original, and ornamental Design for a Vestee, of which the following is a specification, reference being had to the accompanying drawing, forming part thereof, in which—

Fig. 1 is a view of one face of a vestee showing my new design, in untied position;

Fig. 2 is a view of the opposite face thereof; and

Fig. 3 is a perspective view of the vestee shown in Fig. 1, in wearing position.

I claim:

The ornamental design for a vestee, as shown.

FLORENCE LUSTIG.
